TOILET PAPER ROLL HOLDER

Lyman S. Lee, Shaker Heights, Ohio, assignor of
twenty-five per cent to William Isler, Cleveland,
Ohio

Application April 4, 1950, Serial No. 153,943

8 Claims. (Cl. 242—55.2)

1

This invention relates, as indicated, to toilet paper roll holders.

A primary object of the invention is to provide a holder of the character described, which is characterized by novel spring means designed to retain a roll of toilet paper on the holder, while permitting a new roll to be slipped onto the holder, as well as removal of an old roll from the holder, with a minimum of effort, and without the use of tools or the necessity of touching or manipulating the spring means.

Another object of the invention is to provide a holder of the character described, in which said spring means is so constructed and arranged as to resist removal or displacement thereof, without mutilation of same.

A further object of the invention is to provide means for rendering inoperative the action or function of the spring means, whereby surreptitious removal of the roll of toilet paper is rendered difficult.

A still further object of the invention is to provide a holder of the character described, which consists of a minimum number of parts which are easy to manufacture and assemble, whereby the holder can be sold at a low price.

Other objects and advantages of the invention will be apparent during the course of the following description.

In the accompanying drawings, forming a part of this specification, and in which like numerals are employed to designate like parts throughout the same,

Fig. 1 is a bottom plan view of a toilet paper roll holder embodying the invention;

Fig. 2 is an end or side elevational view of the holder, as viewed from the right of Fig. 1;

Fig. 3 is a view, partly in elevation, and partly in section, taken on the line 3—3 of Fig. 2;

Fig. 4 is a fragmentary view similar to Fig. 3, 40 but showing a modification, and

Fig. 5 is a view similar to Fig. 4, but showing another modification.

Referring more particularly to Figs. 1, 2 and 3 of the drawings, the holder will be seen to comprise a bracket or pedestal portion 1, having a flat base 2, which is adapted for securement to a vertical wall, as by means of screws passed through openings 3.

The holder further includes a hollow cylin-

2

drical portion, formed integrally with the bracket 1, said portion being closed at one end by an end wall 5, and open at its other end, a rectangular opening or recess 6 being formed at the open end, which recess extends parallel with the axis of the portion 4.

For the purpose of closing the open end of the cylindrical portion 4 of the holder, a substantially hemispherical cap or button 7 is provided, 10 which abuts the end of the portion 5 and has a portion 8, of reduced diameter, which extends into the cylinder, and facilitates assembly of the cap with the cylinder.

The aforesaid parts are preferably molded from a plastic, which may be a colored plastic, to match various bathroom color schemes, and the cap 8 may be adhesively secured to the other part, as by means of acetone or similar material ordinarily used for uniting plastic parts.

The holder also includes a spring, made from a single piece of flat spring steel or the like, bent to provide an elongated body portion 9, an end portion 10, which extends at an acute angle to the body 9, a portion 11, which extends at an obtuse angle to the body 9, and an end portion 12, which extends substantially perpendicularly to the portion 11.

The spring may be inserted into the cylindrical portion 4 of the holder, prior to assembly of the cap 7 with said portion of the holder, or, if desired, the spring may be inserted into the holder through the opening 6, as by first entering the portion 10 of the spring into the opening, and then moving the spring to the solid line position shown in Fig. 3, with the portions 11 and 12 thereof projecting from the opening 6. In the unstressed condition of the portion 10 of the spring, such portion is at a less acute angle to the body 9 than shown in Fig. 3, so that after the spring has been inserted in the holder, the portion 10 tends to spring upwardly, or in a counter-clockwise direction, as viewed in Fig. 3, so that its upper or free end bites into or frictionally engages the inner wall of the cylinder. This is of advantage in that it enables the spring as a whole to remain in proper position, and prevents, or at least renders difficult, removal of the spring, without mutilation thereof. It will also be noted that the spring, after being properly

positioned, cannot move longitudinally of the cylinder.

With the spring thus positioned within the holder, it will be noted that both the portions 11 and 12 thereof extend at an acute angle to the axis of the cylindrical portion 4 of the holder. This enables a roll of toilet paper to be slipped onto the holder or removed from the holder by a simple manual movement, without the necessity of touching or manipulating the spring by means of the hands or extraneous tools.

In mounting a roll of toilet paper, indicated by the dot-dash lines in Fig. 3, the roll is slipped over the cap 8 and onto the cylindrical portion 4 of the holder. As the roll engages the portion 12 of the spring, incidental to this movement, the portions 9, 11 and 12 of the spring are biased inwardly to the broken line position shown in Fig. 3 and after the roll has passed the portion 11 of the spring, the parts 9, 11 and 12 reassume their normal, or solid line position. The tendency of the parts 11 and 12 of the spring to move radially outwardly from the cylinder is sufficient to prevent the roll of toilet paper from being accidentally or inadvertently pushed off the holder, but is not sufficient to prevent removal of the roll by a simple, easy pulling action to the right, as viewed in Fig. 3.

In thus removing the roll from the holder, the right end of the roll engages the portion 11 of the spring causing the parts 9, 11 and 12 to be biased upwardly to the broken line position shown in Fig. 3, and after the roll has passed the portion 12 of the spring, the parts 9, 11 and 12 reassume their normal or solid line position.

It is thus seen that the construction of the spring is such as to permit a roll of toilet paper to be mounted on or removed from the holder with a minimum of effort, and without the use of tools.

Since the opening 6, in the construction shown, will normally face the wall of the bathroom, the opening and the spring parts 11 and 12 will normally be concealed from the view of a person within the bathroom. As a consequence, there will be little or no temptation to remove the spring or the roll of paper, either maliciously, or as a prank. In a private home, the possibility of the spring being removed from the holder is virtually non-existent. However, there is such a possibility in cases where the present holder is installed in a public lavatory, or in an office building or hotel room. In order to minimize this possibility, the modifications shown in Figs. 4 and 5 are provided.

In Fig. 4, the cap 7' has an axial extension 13, in which a rod 14 is mounted, the rod having a slotted head 15 at one end, and a pin 16 at the other end, extending radially to the rod. After a roll of paper has been placed on the holder, the rod 14 is rotated to move the pin 16 from the position shown in dotted lines in Fig. 4 to the position shown in solid lines, in which latter position, the pin acts to prevent the spring from being biased upwardly. In this way, removal of the spring or the roll of paper is prevented or discouraged, since an observer is not likely to see any functional relationship between the head 15 of the rod and the spring. When the empty roll is to be removed, the pin 16 is returned to the dotted line position.

In Fig. 5, the cap 7" has a slot 17, permitting the cap to be rotated relatively to the cylinder 4. The cap has a portion 8" of reduced diameter, provided with a circumferentially-extending bead

18, which snaps into a groove 19 in the cylinder, for the purpose of securing the cap to the cylinder. This snapping connection, as well as removal of the cap, is facilitated due to the resiliency or expansibility of the end of the cylinder created by the provision of the recess or slot 6. The cap is further provided with a detent 20, formed integrally with the cap. After a roll of paper has been placed on the holder, the cap is rotated, as by means of a screw driver inserted into the slot 17, to move the detent 20 from the position shown in solid lines in Fig. 5 to the position shown in broken lines, in which latter position, the detent acts to prevent the spring from being biased upwardly. In this way, removal of the roll of paper is prevented or discouraged, since an observer is not likely to see any functional relationship between the cap 7" and the spring. When the empty roll is to be removed, the detent is returned to the solid line position.

The holders, as described, can be manufactured at extremely low cost, since they include a minimum of parts, which are easy to manufacture and assemble.

It is to be understood that the forms of my invention, herewith shown and described, are to be taken as preferred examples of the same, and that various changes in the shape, size and arrangement of parts may be resorted to, without departing from the spirit of my invention or the scope of the subjoined claims.

Having thus described my invention, I claim:

1. In a holder of the character described, a cylinder having an end over which a roll of paper may be slipped, and spring means for retaining said roll on said cylinder, said spring means having angularly related non-circular portions, extending externally of the cylinder and at an acute angle to the axis of the cylinder, one of said portions engageable by the roll when the roll is slipped onto the cylinder and the other of said portions being engageable by the roll when the roll is slipped off the cylinder, both of said portions being disposed closely adjacent said end of the cylinder, and the cylinder being of sufficient length that the roll, when disposed in usable position on the cylinder, is not engaged by either of said portions of the spring.

2. A holder, as defined in claim 1, in which said cylinder has a slot in the wall thereof adjacent said end, and said spring portions project outwardly from said cylinder through said slot.

3. In a holder of the character described, a cylinder having an end over which a roll of paper may be slipped, and spring means for retaining said roll on said cylinder, said spring means having angularly related straight portions, both extending at an acute angle to the axis of the cylinder, one of said portions engageable by the roll when the roll is slipped onto the cylinder and the other of said portions being engageable by the roll when the roll is slipped off the cylinder, both of said portions being disposed closely adjacent said end of the cylinder, and the cylinder being of sufficient length that the roll, when disposed in usable position on the cylinder, is not engaged by either of said portions of the spring.

4. A holder, as defined in claim 3, in which said cylinder has a slot in one end thereof, and said spring portions project outwardly from said slot.

5. A holder, as defined in claim 4, in which said spring has a body portion extending substantially parallel with the axis of said cylinder and lying closely adjacent the inner wall of the cylinder.

6. A holder, as defined in claim 5, in which said body portion extends to the other end of said cylinder and said spring has a portion extending from said other end of the cylinder at an acute angle to said body portion to the diametrically opposite wall of the cylinder, engaging said wall, whereby removal of said spring, without mutilation thereof, is rendered difficult.

7. A holder, as defined in claim 6, in which said body portion of the spring is insertable into said cylinder through said slot even with both ends of the cylinder closed.

8. A holder, as defined in claim 7, in which said spring is adapted to be biased inwardly of the cylinder when the roll is slipped onto or off the 15

cylinder, and means are provided to prevent inward biasing of said spring, whereby removal of the roll from the cylinder is prevented, when desired.
